UNITED STATES PATENT OFFICE

2,523,894

ROCKERLESS ROCKING CHAIR

Raymond H. Arf and Bernard G. Beier,
Minneapolis, Minn.

Application May 22, 1946, Serial No. 671,518

1 Claim. (Cl. 155—56)

1

Our invention relates to improvements in rocking chairs of the type commonly referred to as porch or lawn chairs.

An object of this invention is to provide guards to prevent a person sitting in the chair from getting their fingers and clothing pinched by movable parts of the chair.

Another object of this invention is to provide positive means that limits the forwardly rocking of the chair when a person is getting in or out of the chair.

A further object of the invention is to provide a rocking chair that is strong, durable, and attractive.

A still further object of the invention is to provide a chair having free and easy rocking action.

Other objects of the invention will be apparent from the following description, reference being had to the drawing.

To the above end, generally stated, the invention consists of the novel construction, arrangement and combination of parts.

In the accompanying drawing, which illustrates the invention, like characters indicate like parts throughout the several views.

Referring to the drawing:

Fig. 1 is a side elevation of the improved rocking chair;

Fig. 2 is a front elevation of the same;

Fig. 3 is a fragmentary detail view partly in elevation and partly in section taken on the line 3—3 of Fig. 1;

Fig. 4 is a fragmentary detail view partly in elevation and partly in section taken on the line 4—4 of Fig. 2; and

Fig. 5 is a fragmentary detail view partly in side elevation and partly in section taken on the line 5—5 of Fig. 2.

The improved rocking chair includes a pair of laterally spaced base bars 5, a rectangular back frame 6 and a rectangular seat frame 7. The back frame 6 includes a pair of side bars 8, a top or head cross-tie bar 9 and a bottom cross-tie bar 10, the end portions of which project outwardly of the side bars 8, under the side bars 13, and serve as stops 11 as will presently appear. These cross-tie bars 9 and 10 are rigidly connected to the side bars 8 by nut-equipped bolts 12.

The seat frame 7 comprises a pair of laterally spaced side bars 13. Two relatively narrow, closely positioned cross-tie bars 14 and 15 and a bottom cross-tie bar 16. Nut-equipped bolts 17 rigidly connect the cross-tie bars 14, 15 and 16 to the side bars 13.

The two frames 6 and 7 are in crossed arrange-

ment with the back frame 6, extending through the seat frame 7. The back frame 6 is rearwardly inclined and the lower end portions of its side bars 8 overlap the base bars 5 on the inside near the front end portions thereof. Nut-equipped bolts 18 pivotally connect the side bars 8 to the base bars 5. Spacing washers 19 on the bolts 18 are interposed between the base bars 5 and the side bars 8 to permit free swinging movement of the back frame 6 relative to the base bars 5.

The seat frame 7 is forwardly inclined and the lower end portions of its side bars 13 overlap the base bars 5 on the outside, near the rear thereof. Nut equipped bolts 20 pivotally connect the side bars 13 to the base bars 5. Spacing washers 21 on the bolts 20 are interposed between the base bars 5 and the side bars 13 to permit free swinging movement of the side frame 7 relative to the base bar 5.

Guards 22 in the form of wide vertically disposed boards are interposed between each pair of side bars 8 and 13 at their points of intersection. Nut-equipped bolts 23 pivotally connect the guards 22 to the side bars 8 and nut-equipped bolts 25 pivotally connect the guards 22 to the side bars 13. The guards 22 also serve as links that connect to bars 8 and 13 of each pair, above their points of intersection. Spacing washers 25 on the bolts 23 and 24 are interposed between the side bars 8 and 13, and the guards 22 and permit free oscillatory movements of said side bars and guards. These guards 22, are in the same planes as the base bars 5; fill the spaces between side bars 8 and 13 of each pair, extend materially both forwardly and rearwardly of the crossed portions of said side bars and prevent the fingers and clothing of a person sitting in the chair from getting pinched between the bars 8 and 13 of each pair during the rocking of said chair.

Rigidly secured to each of the guards 22 at their upper edges is a wide outwardly extended arm rest 26.

A fabric strip 27 that serves as a seat and back for the chair has one of its end portions wrapped around the cross-tie bar 9 and secured to the front edge thereof by tacks or nails 28. The strip 27, at its lower end portion, is wrapped around the cross-tie bars 14 and 15 and onto the top of said bar 15 and is secured thereto by tacks or nails 29. A piece of carpet, felt, or other cushioning material 30 is wrapped around the cross-tie bar 14 before the fabric strip 27 is attached thereto.

Extreme forward rocking movement of the

chair is limited by the engagement of the side bars 13 with the stops 11, over and across which they extend.

A head rest 31, is secured by screws 32, to the side bars 8, above the cross-tie bar 9.

From what has been said, it will be understood that the rocking chair described, is capable of various modifications as to details of construction and arrangement within the scope of the invention herein disclosed and claimed.

What we claim is:

A chair of the class described, comprising a pair of laterally spaced base bars, a rearwardly inclined back frame, a forwardly inclined seat frame, each of said frames comprising a pair of side bars and upper cross-tie bars, one of said frames being extended through the other thereof in crossed arrangement, the side bars on each side of the chair being on opposite sides of the respective base bar and pivoted thereto and a fabric seat and back strip attached to the upper cross-tie bars of the two frames, a guard extend-

ing between the side bars, on each side of the chair at their points of intersection and filling the space therebetween, said guards being pivoted to the side bars above their points of intersection.

RAYMOND H. ARF.
